W. A. BENSON

AUTOMATIC TELEPHONE SYSTEM

Filed June 13, 1921

UNITED STATES PATENT OFFICE.

WILLIAM A. BENSON, OF CHICAGO, ILLINOIS, ASSIGNOR TO AUTOMATIC ELECTRIC COMPANY, OF CHICAGO, ILLINOIS, A CORPORATION OF ILLINOIS.

AUTOMATIC TELEPHONE SYSTEM.

Application filed June 13, 1921. Serial No. 477,183.

To all whom it may concern:

Be it known that I, WILLIAM A. BENSON, a citizen of the United States of America, and a resident of Chicago, Cook County, 5 and State of Illinois, have invented certain new and useful Improvements in Automatic Telephone Systems, of which the following is a specification.

The present invention relates in general 10 to automatic telephone systems; and the particular object of the invention is to provide means, when a busy line is called, for notifying the subscriber on the called busy line that a connection is desired with his 15 line.

The above and other objects of the invention will be described fully hereinafter with reference to the accompanying drawing.

20 Referring now to the drawing at A is shown a subscriber's substation of the usual automatic type. The line conductors extending to the substation terminate at the exchange in an individual trunk selecting 25 or line switch C. This line switch is of the well known rotary type whose wipers have no normal position, always remaining, when idle, in engagement with the bank contacts associated with the trunk line last used. 30 The line switch C, in common with a plurality of other line switches, has access to trunk lines extending to connector switches, one of these being shown at H.

The connector H is of the usual Strowger 35 vertical and rotary type, the circuits of which have been modified in accordance with the features of my invention. The connector H has access to called lines such as the one shown associated with the substation A'. At the exchange the line of the substation A' terminates in the individual line switch C'.

40 At I is shown a constantly operating interrupter the function of which will be explained hereinafter.

45 While in the drawing the line switch C is shown having access directly to connector switches, it will be readily apparent that as many selectors as are necessary could be inserted before the connector H depending upon the size of the system.

50 Having briefly described the apparatus shown in the drawing, a detailed description of the operation will now be given.

For this purpose it will be assumed that 55 the subscriber at substation A desires to call the subscriber at substation A'. In order to do this the subscriber at substation A will remove his receiver and operate his calling device S in accordance with the two 60 digits of the number of the desired called subscriber. When the receiver is removed at substation A, a circuit is completed for the line relay 16 of the line switch C over the line conductors 11 and 12 in series. Relay 16, upon energizing, at its armature 24 completes a circuit which includes the switching relay 15 and the motor magnet 17 in series, and at its armature 23 connects the test wiper 28 to the above circuit at 70 a point midway between the switching relay and the said motor magnet. The operation of the line switch C now depends upon whether the trunk line with which the switch wipers 27-29, inclusive are in engagement is busy or idle. Assuming that the trunk line is busy, there will be a ground potential present upon the test contact engaged by the test wiper 28 and the motor magnet being supplied with direct ground 80 via the said test wiper will operate as a buzzer to advance the switch wipers step by step in search of an idle trunk line. However, it will be assumed that when the receiver is removed at substation A the 85 wipers of the line switch C are in engagement with the trunk line comprising conductors 30-32, inclusive, and it will be assumed further that this trunk line is idle. Under these conditions, immediately following the energization of the line relay 16, switching relay 15 energizes. It may be stated at this point that the switching relay 15 is of sufficiently high resistance to prevent the energization of the motor magnet 17 in series with it. Upon energizing, relay 15 disconnects the line conductors 11 and 12 of the substation A from the winding of the line relay 16 and from ground, respectively, and extends them by way of armatures 20 and 22, wipers 27 and 29, bank contacts 30 and 32, normally closed springs controlled by armatures 58 and 59, to the upper and lower windings of the line relay 51 of the connector H.

100 The line relay 51 is immediately energized over the calling line loop and, upon operating, completes the circuit of the slow

acting release relay 52. Relay 52, upon operating, prepares the impulsing circuits of the connector H at armature 67 and at armature 66 places ground on release trunk conductor 49 thereby establishing a holding circuit for line switch C. This circuit extends by way of the test contact 31, test wiper 28, armature 21 and its front contact, winding of the switching relay 15, and 5 thence through the winding of the motor magnet 17 to battery. This circuit serves to maintain the switching relay 15 operated throughout the connection. A branch of the holding circuit also extends by way of 10 the private normal conductor 35 to multiply connected test contacts in the banks of connector switches which have access to the line of the substation A whereby the said line is protected from intrusion in the usual 15 manner.

The subscriber at substation A may now operate his calling device in accordance with the first digit of the desired called subscriber's number. By this operation a series 20 of interruptions is produced in the circuit of the line relay 51 of the connector H and this relay retracts its armature a plurality of times in response thereto. At each retraction of its armature 60, an impulse of 25 current is sent from ground by way of the armature 60 and its back contact, armature 67 and its front contact, off normal springs 63 and 62, through the winding of the slow acting relay 53 and thence through the winding 30 of the vertical magnet 88 to battery. The above is the circuit over which the first impulse to the vertical magnet is sent. However, upon the first vertical step of the switch, the off normal springs are shifted 35 and the remaining impulses to the vertical magnet traverse a new circuit which is the same as the one previously traced except that it includes the off normal springs 63 and 64 and armature 58 and its front contact, relay 40 45 53 being now in an operated position. Vertical magnet 88 operates to raise the switch wipers 90-92, inclusive, step by step until they are placed opposite the level of bank contacts in which is located the contact set 50 associated with the line of the called substation A'. The slow acting relay 53 is energized in series with the vertical magnet and maintains its armature attracted throughout the vertical movement of the switch, and at the termination thereof de- 55 energizes and transfers the impulsing circuit to the rotary magnet 87.

The calling subscriber may now operate his calling device in accordance with the 60 next and final digit of the desired number. As before, a series of interruptions is produced in the circuit of the line relay 51, which deenergizes a corresponding number of times, each time sending an impulse of 65 current over the following circuit: ground

by way of armature 60 and its back contact, armature 67 and its front contact, off normal springs 63 and 64, armature 68 and its back contact, back contact and armature 75, armature 84 and its back contact, through 70 the winding of the rotary magnet 87 to battery. The rotary magnet 87 operates to rotate the switch wipers into engagement with the set of bank contacts associated with the line of the desired substation A', which we 75 will assume, are the bank contacts 93-95, inclusive. The slow acting relay 56 is energized in multiple with the rotary magnet and operates at its armature 79 to connect the test wiper 91 with the test relay 55. 80

Assuming that the line of the substation A' is idle, there will be no ground potential present upon the test contact 94 engaged by the test wiper 91 and no circuit will be completed for the test relay 55. Then, following the deenergization of the slow acting relay 56, a circuit is completed which may be traced from ground on release trunk conductor 49, armature 74 and its back contact, lower winding of the switching relay 57, 90 back contact and armature 79, test wiper 91, test contact 94, through the winding of the switching relay 96 of the line switch C', and thence through the winding of the motor magnet 98 to battery. Relays 57 and 96 are 95 energized over this circuit. However, due to a mechanical interlocking device controlled by the armature of the line relay 97 which is now normal, the switching relay only partially operates its armatures, that is, enough to disconnect the line of the substation A' from its normal battery and ground connections in the line switch C'. Relay 57, upon energizing, establishes a locking circuit for itself at its armature 83 and at its armatures 83 and 85 completes the ringing circuit. Ringing current from the generator Gen is intermittently applied to the line of 100 substation A' until the subscriber thereat responds.

When the called subscriber removes his receiver, the ring cut off relay 54 is energized over the called line loop and, upon operating, establishes a locking circuit for itself at its armature 71, at its armatures 70 and 72 opens the ringing circuit, and at the front contacts of these armatures finally completes the talking connection. Talking battery is supplied to the called subscriber from the windings of the back bridge relay 50 which is immediately energized over the called line and operates to reverse the normal current flow over the calling line loop for supervisory or metering purposes. The conversation may now take place between the calling subscriber at substation A and the called subscriber at substation A', the calling subscriber being supplied with talking battery from the windings of the line relay 51.

When the conversation is terminated, both 130

- subscribers will replace their receivers upon their respective switchhooks. When the receiver is replaced at substation A, the circuit of the line relay 51 is opened and this relay accordingly deenergizes. Relay 51, upon retracting its armature 60, opens the circuit of the slow acting relay 52 which deenergizes removing ground from the release trunk conductor 49 at armature 66 and at 5 armature 67 completing the circuit of the release magnet 86 of the connector H. The magnet 86 operates to restore the connector H to normal in the usual manner. Upon 10 ground being removed from the release trunk conductor 49 the holding circuit of the switching relay 15 in the line switch C is opened and this relay then deenergizes thus restoring the line switch to normal position.
- 15 The above is the normal operation of the system when the line of the called substation A' is idle and follows the usual practice. However, should the line of the substation A' be busy either from initiating the call or from being called, it becomes necessary 20 in accordance with the features of the invention to notify the subscriber at substation A' that he is being called. This operation will now be described. For this purpose it 25 will be assumed that when the switch wipers 90-92, inclusive, of the connector H are rotated into engagement with the contact set associated with the line of the substation A', the called line is busy. Under these 30 conditions, there will be a ground potential present upon the test contact 94. This ground will be placed on the test contact 94 whether the subscriber at substation A' is 35 busy from being called or initiating the call.
- 35 If initiating a call, contact 94 will be grounded by way of the release trunk conductor extending to the connector in use; while if the line of the substation A' is being called, there will be a ground potential 40 on the contact 94 from the test wiper of the connector switch which has established connection with the line. Immediately upon the 45 switch wipers 90-92, inclusive, being rotated into engagement with the bank contacts 93-95, inclusive, a circuit is completed 50 which extends from the grounded test contact 94 by way of test wiper 91, armature 79 and its front contact, armature 81 and its back contact, and thence through the winding 55 of the test relay 55 to battery. Relay 55, upon energizing, prepares a point in its locking circuit at armature 74 which is closed immediately upon the deenergization of the slow acting relay 56. Another result of the 60 energization of relay 55 is that a busy tone from the busy machine is placed on the lower heavy talking conductor at armature 76 which is audible to the calling subscriber. A still further result of the energization of 65 relay 55 is that a light tone is placed on the
- called subscriber's line over a circuit extending from the tone conductor 119, armature 73 and its front contact, armature 77 and its back contact, back contact and armature 80, wiper 90, bank contact 93, and thence 70 over the line of the called substation A'. This tone serves to inform the subscriber at substation A' that he is being called, but it is quite low and does not appreciably interfere with the conversation. When the subscriber at substation A hears the busy tone, 75 he will replace his receiver upon the switchhook and then release the operated switches in the same manner as was described hereinbefore. The subscriber at substation A' 80 being notified that he is being called by the above mentioned tone will, in all probability, terminate the conversation as soon as possible thereby rendering his line accessible to be called and thus lessening the time during 85 which his line is held busy.
- At this point the operation of the interrupter I in producing the low induced tone which is placed on the busy called subscriber's line will be described a little more 90 in detail. The interrupter I is made up of two coils 100 and 101 above which is pivoted an armature, 105. Attached to the armature 105 is a swinging pendulum 102. As the pendulum 102 moves back and forth it 95 closes the circuit of the coils 100 and 101 at the proper point in its arc as it is connected to battery. That is, assuming that the pendulum 102 is moving to the right under influence of the coil 100 it will break 100 contact with the contact 103 thereby opening the circuit of the coil 100 and shortly after close the contact 104 thereby closing the circuit of the coil 101. Upon energizing, 105 the coil 101 attracts the armature 105 and causes the pendulum 102 to move in the opposite direction. The speed of the pendulum may be regulated by means of the weight 125 which is held in position by the set screw 126. The weight 125 is preferably 110 quite heavy so as to make the pendulum 102 slow moving. Each time the pendulum moves back and forth, its upper end engages the spring 109 and causes it to break contact with the spring 106. However, there is 115 a short interval when all the three contacts are making, that is, the pendulum 102, the spring 109 and the spring 106. At this instant, there is an impulse of battery sent over the conductor 123 and through the coil 111 to ground. As the pendulum 102 and the spring 109 make and break contact, the condenser 112 is charged and discharged 120 through the upper winding of the coil 110. The current fluctuation in the coil 110 serves to induce a secondary alternating current in the lower winding of the coil 110 and thence through the condenser 113 to the tone lead 119. In order to secure the best 125 operation the condenser 112 is of relatively 130

- large capacity as compared with the condenser 113. Also the upper winding of the coil 110 has a great many more turns on its winding than has the lower winding of the coil 110. This is so as to get a sufficient volume of pulsating current to supply a number of tone leads. The tone lead 119 is common to a group of connector switches which have access to 100 lines. In the case of a large system where there are a number of groups of 100 lines each group of connectors will be supplied with a tone lead such as 120 and 121 and a condenser individual to each lead such as 114 and 115. It will be seen that the above construction will give a slow click tone signal to any subscriber on a called busy line, which is so light that it does not interfere in any way with the conversation.
- Having fully described and ascertained the features of the invention, what is considered to be new and desired to have protected by Letters Patent will be pointed out in the appended claims.
- What I claim is:
1. In a telephone system, a calling and a called line, an automatic switch controlled over said calling line to connect with said called line in an attempt to establish a talking connection therewith, a switching relay for connecting the wipers of said switch, a test relay responsive in case the called line is busy to open the circuit of said switching relay, a source of signalling current, and a circuit controlled by said
  2. In a telephone system, a calling and a called line, an automatic switch controlled over said calling line to connect with said called line in an attempt to establish a talking connection therewith, a switching relay for connecting the wipers of said switch, a test relay responsive in case the called line is busy to open the circuit of said switching relay, a source of signalling current, and a circuit for connecting said source to one of the wipers of said switch to signal the called subscriber while his line is busy, said circuit including normally closed contacts on said switching relay and normally open contacts on said test relay.
  3. In a telephone system, a calling and a called line, an automatic switch controlled over said calling line to connect with said called line in an attempt to establish a talking connection therewith, a test relay in said switch effective to prevent the completion of such talking connection if the called line is busy, a source of busy signalling current, another source of signalling current, circuits for connecting the first of said sources to the calling line and the second of said sources to the called line, and contacts on said test relay included in both said circuits for closing the same when the test relay is energized.

In witness whereof, I hereunto subscribe my name this 9th day of June, A. D. 1921.

WILLIAM A. BENSON.
